Preco Incorporated, Los Angeles, Calif., a cor-
poration of California

Application December 21, 1948, Serial No. 66,530

15 Claims. (Cl. 74—242.15)

1

This invention relates generally to mechanisms for transmitting power between shafts which are subject to appreciable relative translational movement. Such transmissions are particularly useful, to cite a typical application, for transmitting power from the running gear of a railway car to accessories of various kinds mounted on the car body.

An important object of the present invention is the provision of a transmission suitable for driving accessories such, for example, as air circulating fans in railway express refrigerator cars. In such cars the lateral shifting of the wheels with respect to the car is appreciably greater than is ordinarily encountered in standard refrigerator cars, both because of the relatively soft springs with swing hangers, and because of the greater truck spacing and the greater separation of the axles on each truck. This difficulty is met by providing a drive mechanism which is particularly adapted for taking its initial drive from a drum mounted on the central part of an axle, where the drum can be wide enough to accommodate the lateral displacements relative to the body caused both by lateral translational motion of the truck and by its rotation. A further advantage of taking the drive from a drum rather than from the car wheel is that the radius of the drum can be varied to limit the maximum peripheral speed of the driving element, and thereby to limit the speed of the driven element without unreasonably increasing its diameter. Although the present invention is particularly adapted for such service, it is also broadly applicable in mechanisms driven from any suitable element of the wheel and axle unit, including the car wheel, and for service on cars of various types.

In preferred form, the present drive mechanism makes use of a drive shaft which is connected by suitable transmissions, on the one hand, to an element driven from the car wheel and axle unit and, on the other hand, to the shaft of the accessory to be driven. That overall structure has great flexibility of arrangement, and is therefore suitable for driving accessories of various types and located in various positions in or on the car body. Under certain conditions, the accessory shaft can be substituted directly for the driving shaft of the preferred form of the device. The second transmission described above is then omitted.

The invention includes provision for disabling the transmission between the drive shaft and the accessory shaft, where those shafts are distinct,

2

and for disabling the driving connection between the wheel and axle unit and the element directly driven thereby. In preferred form, both those disabling operations are performed by manual shifting of a single lever from one stable position to another. With the lever in transmission disabling position the entire drive mechanism is disconnected from the car wheels, allowing the car to be moved without driving the accessory and also without wearing any parts of the drive mechanism; and is also disconnected from the accessory, permitting the latter to be driven from any suitable auxiliary power source, such as an electric motor, when the car is stationary, such auxiliary drive being unrestrained by, and causing no wear of, the driving mechanism of the invention.

Provision is made, when the drive mechanism is in operating position, for maintaining the two transmissions mentioned above, and also the driving engagement with the wheel and axle unit, in fully effective condition. In a preferred modification of the invention, that threefold function is performed by means of a single spring element. The structure of the device is such that the effective force applied by that spring element to each of the three transmission stages can be independently varied over wide limits by modifications of the detailed design, or by providing adjustments by which such modifications can be readily introduced.

A clear understanding of the invention will be had from the following detailed description of a specific mechanism of preferred form in which it is embodied. That description is illustrative of the invention and will form a basis for further discussion of it, but the particular structure described and illustrated in the accompanying drawings is intended as typical and not as limiting either the range of structural modifications or the conditions of application of the invention.

In the drawings:

Fig. 1 is a side elevation, partially cut away, showing a portion of a railway car equipped with a typical drive mechanism in accordance with the invention;

Fig. 2 is a fragmentary horizontal section, taken just below the side sill on line 2—2 of Fig. 1;

Fig. 3 is a fragmentary section in the same aspect as Fig. 1, taken generally on line 3—3 of Fig. 2 but with the car wheel omitted;

Fig. 4 is a fragmentary section in the same aspect as Fig. 1, taken generally on line 4—4 of Fig. 2, and showing the drive mechanism in non-operating position;

Fig. 5 is a fragmentary section on the lines 5—5 of Figs. 1 and 2;

Figs. 6 and 7 are schematic diagrams, related to Fig. 3 and illustrating modifications; and

Fig. 8 is an elevation taken transversely of the car, as indicated by the line 8—8 in Fig. 1.

In the drawings the car structure, which is shown somewhat schematically, includes the side sill 10 and the center sill 12 of the car under-frame. As illustrated, the center sill is of double construction, and only one of the transversely spaced members of the complete sill appears in the drawings. An important advantage of the present driving mechanism is that it can be mounted on the car entirely by means of connections to those two members of the car frame. Although other methods of connection to the car are included within the scope of the invention, it is preferred to make use of those two members, and for this reason other portions of the car body are mainly omitted in the drawings.

A wheel and axle unit is indicated at 15, including the car wheel 16 and the axle 17. The structure of the car truck, on which axle 17 is journaled in the usual way, is omitted for clarity of illustration, it being understood that unit 15 is movable in the usual manners within certain limits relative to the car body.

The accessory to be driven is typically represented as an air circulating fan of the type disclosed in the Van Dorn Patents 2,214,210 and 2,349,315. Such a fan is indicated in end elevation at 20 in Figs. 1 and 4, and in side elevation in Fig. 8, its operating shaft 22 protruding from one end of the fan case and carrying the sheave 24. A fan of the type shown is normally placed directly above the car floor 25, with its shaft 22 transverse of the car and with sheave 24 approximately in the plane of one car side wall. Although the present illustrative arrangement of the invention is particularly adapted for driving such an accessory, the drive mechanism can be accommodated to other types of accessory and other placements of the accessory shaft, including its relation both to the car floor and to the longitudinal car axis.

In the present embodiment, the main drive shaft 26 of the driving mechanism is journaled in a shaft housing 28 which is mounted transversely of the car, preferably beneath the car floor as indicated in the drawings. Shaft 26 is connected at its outer end to accessory shaft 22 by means of a transmission 30 which, in the present instance, lies substantially in the plane of the car side wall, and has its axis 31 generally vertical. Transmission 30 comprises typically a belt 32 passing over sheave 24 on accessory shaft 22 and a sheave 34, fixed on driving shaft 26. The inner end of shaft 26 is driven from car and axle unit 15 by means to be described.

Shaft housing 28 is mounted on the car body, its inner end being preferably supported on car center sill 12 and its outer end on car side sill 10. Those mountings are of any suitable type which permit rotation of the housing about its longitudinal axis through at least a small angle, and translational motion of the outer end of the housing along transmission axis 31. As illustrated, the inner mounting comprises the rubber bushing 36 which surrounds shaft housing 28 and is itself mounted in an aperture in a plate 37, supported by means of bracket 38 on center sill 12. Bushing 36 is sufficiently flexible to permit the two types of housing motion just mentioned,

functioning as the substantial equivalent of a ball joint.

The outer end of shaft housing 28 rests in a yoke 40 formed at one end of a generally horizontal lever 41 which is pivoted at 42 on plate bracket 40 (see below) for swinging movement about a pivot axis generally parallel to the shaft. Thus downward translational motion of the outer end of shaft 26, which tightens belt 32 and renders transmission 30 effective, is permitted by clockwise rotation of lever 41 on its pivot 42 (as seen in Figs. 1 and 4) and involves swinging movement of the shaft and its carrier about an axis transverse of the shaft through its inner support 36. Counterclockwise rotation of lever 41 swings the shaft and housing upward about its flexible inner support 36, and moves sheave 34 closer to accessory shaft 22, disabling transmission 30 (Fig. 4). The axial position of yoke 40 with respect to shaft housing 28 is defined by collars 45, which thereby establish the axial position of the shaft housing with respect to the car body. The fit of yoke 40 around the shaft housing and between collars 45 is preferably sufficiently loose to allow the described swinging movement of the shaft about its inner support 36, lever 41 being confined to movement in a plane normal to the axis of pivot 42. Alternatively, lever 41 may be loosely pivoted at 42 to accommodate the swinging movement of shaft housing 28.

The mechanism by which shaft 26 is driven from wheel and axle unit 15 is shown best in Figs. 2 and 3. A drum 55 with a flanged edge 56 is rigidly mounted on the central portion of axle 17 and serves as initial driving element in the preferred embodiment illustrated. However, the drive may be taken alternatively from any suitable element which rotates with the car wheels, such as the axle 17, or the rim of a wheel 16. As used in the present specification and claims, the term "drum" is intended to include such functional equivalents of the illustrative specific driving element 55. A roller 60, preferably carrying a rubber tire, is rigidly mounted with sheave 63 on a roller shaft 62. Shaft 62 is journaled in a bracket arm 64 which is swingable about an axis (66) generally parallel to axle 17 and to roller shaft 62. Swinging movement of arm 64 in one direction (counterclockwise as seen in Figs. 1, 3 and 4) brings roller 60 into driven engagement with the periphery of drum 55, establishing an effective transmission between axle 17 and shaft 62. That transmission is disabled by swinging movement of arm 64 in the opposite (clockwise) direction, which lifts roller 60 clear of the drum.

A transmission 80 is provided between roller shaft 62 and drive shaft 26, and comprises the sheave 63 fixed on roller shaft 62, the sheave 84 fixed on the inner end of drive shaft 26, and the belt 86 passing over those two sheaves. The axis of transmission 80 lies in the plane of shafts 26 and 62, and the transmission is rendered effective by translational movement of roller shaft 62 along that axis away from shaft 26 to tighten belt 86. Bracket arm 64 is so mounted as to provide that movement of roller shaft 62 in addition to, and independently of, the swinging movement of the arm which controls the effectiveness of the transmission from drum 55.

In the present preferred form of the invention, bracket arm 64 is pivoted on a toggle axis 66 at the free end of a toggle link 68. As illustrated, toggle link 68 comprises two arms 69

rigidly mounted on shaft housing 28, from which they extend radially in a common plane. Thus the link axis is the longitudinal axis of shaft housing 28, and toggle action of the link involves rotation of arms 69 and shaft housing 28 as a unit about that axis. That rotation in practice is limited to a relatively small angle, and is accommodated at the inner mounting of housing 28 either by flexibility of rubber bushings 36 or by rotation of housing 28 with respect to that bushing. The outer housing support in yoke 48 permits unlimited housing rotation.

Arm 64 is of general channel section, including a curved web plate 70 and depending side flanges 72 which provide bearings or bearing supports both for roller shaft 62 at the free outer end of the arm and for the bent ends of toggle arms 69 at the inner end of the arm. The outer end of web plate 70 forms an offset extension 74, which is braced by gusset plate 76 and is provided at its outer edge with a spring receiving notch 78, formed by a downwardly bent lip 79.

The toggle linkage formed by arm 64 and toggle link 68 is generally parallel to the axis of transmission 30, with both members of the linkage preferably oblique to that axis. Thus relative rotation of the two members of the toggle linkage about toggle axis 66 changes the spacing between shafts 62 and 26, and tightens or loosens belt 86, rendering transmission 30 effective or ineffective, respectively. That control of transmission 30 is independent of the action of arm 64 by which the driving relation between roller 60 and drum 55 is controlled, that action comprising rotation of the entire toggle linkage about the axis of housing 28 and drive shaft 26.

In the illustrated embodiment of the invention unitary spring means are provided which accomplish the three distinct functions, under normal operating conditions of the drive mechanism, of maintaining effectiveness of transmissions 30 and 30 and of urging roller 60 into tractive contact with drum 55. Those functions are accomplished by a spring which exerts pressure at two points of the mechanism which has been described. One of those points is on arm 64, conveniently defined by the notch 78, and the other is an intermediate point of shaft housing 28, that point being preferably defined by suitable spring confining means on the housing, such as the groove 90. In the present illustrative embodiment the spring force at both those points is directed generally downwardly. The force at groove 90 on shaft housing 28 tends to swing the housing and shaft 26 downward about its inner support 36, and thus to tighten belt 32 and render transmission 30 effective between drive shaft 26 and accessory shaft 22. The downward force at 78 tends to rotate arm 64 and toggle link 68 as a unit around the axis of drive shaft 26 in a direction to press roller 60 into effective engagement with drum 55. The position of notch 78 with respect to roller shaft 62, and the direction of application of the spring force at the notch are so arranged that the line of the resulting force upon arm 64, while generally transverse to shaft 62, is spaced from that shaft. Hence the spring force cooperates with the reaction force of drum 55 upon roller 60 (which reaction force is transmitted through shaft 62 to the arm) to form a force couple resulting in a torque on the arm. That torque is so directed as to urge rotation of arm 64 in a suitable direction (counterclockwise in the present instance, as seen in Fig.

3) to actuate toggle linkage 68, to increase the spacing of the shafts 62 and 26, thus tightening belt 86 and rendering effective transmission 30.

The particular spring means employed in the present instance to produce the above described forces at 78 and at 90 is the spring 100 which has a central helically coiled section 102, the axis of which is located with relation to other parts of the mechanism by the rod 106. Guide rod 106 (which is also a part of the transmission disabling mechanism to be described) extends generally transversely to a line connecting the two points 78 and 90 of the spring application, and, in the present preferred form of the device, is parallel to shaft 26. A relatively straight end portion 104 of spring 100 extends generally radially from the inner end of spiral 102 and rests on the upper face of lip 79 in the notch 78 of arm 64. A similar relatively straight end portion 105 of the spring extends generally radially from the outer end of spiral 102 and rests upon the upper surface of shaft housing 28, its longitudinal position on the housing being defined in the present instance by groove 90.

Spring 100 is so loaded that the forces exerted by the spring at the points 78 and 90 are suitable for the functions described. Since the reactive torques about rod 106 exerted upon the spring at 78 and 90 are necessarily equal and opposite, the forces themselves are inversely proportional to the radial distances of those points from the axis of guide rod 106. Hence the relative magnitudes of the forces at 78 and 90 are controllable by selection of the location of guide rod 106 with respect to those points. Given a definite spring force acting on the shaft housing, the resulting force tending to tighten belt 32 can be varied by varying longitudinally the point of spring contact, defined by groove 90. Similarly, the effect of the spring force applied to arm 64 is controllable as to the relation between the spring-induced pressure of roller 60 against drum 55 and the tightness of belt 86. The belt tightening action, resulting from the toggle linkage, can be controlled within wide limits by varying such constants of the mechanism as the various angles of the toggle linkage and the distance from shaft 62 to the line of action of the spring force applied at 78. For example, the smaller the angle between the plane of toggle link 68 and the plane defined by shafts 62 and 26 the greater is the mechanical advantage of the toggle linkage tending to tighten belt 32. Similarly, the greater the distance between the line of action of the spring force at 78 and roller shaft 62 the greater will be the spring-induced couple applied to arm 64 and tending to straighten the toggle linkage. The device illustrated is so proportioned that the toggle actuating couple, and hence the tension on belt 86, is relatively small as compared to the actual spring applied force at 78. That force, on the other hand, is transmitted undiminished to the roller shaft 62, and is even somewhat increased by lever action, point 78 being farther from drive shaft 26 than is the roller shaft. The result of such preferred proportioning of the mechanism is that the drive between roller 60 and drum 55 is relatively more positive than is transmission 30. Hence if accessory shaft 22 or drive shaft 26 is prevented from turning, as by an obstruction of any type in the mechanism, it is belt 86 rather than roller 60 that will slip. Under such conditions the belt wears out and breaks before damage is done to the roller, which is ordinarily relatively expensive and difficult to replace.

Similarly, by the design control which determines the pressure on, and the location of, the point of pressure application 90, the traction on belt 32 may be made less than on belt 86, so that 32, which is usually the more easily replaceable, will slip before 86.

Transmission disabling mechanism is provided, operable by means of a hand lever 109. As illustrated, lever 109 is rigidly connected to a cam 112 which is secured as by a pinning bolt 114 to the outer end of spring guide rod 106 in position to engage the end 43 of lever 41. Rod 106, shown as a tube, is journaled at its inner end in a sleeve 108, welded directly to the lateral face of car center sill 12; and its outer end in an aperture in bracket plate 110. A headed pin 116 axially enters the outer end of hollow rod 106, where it is locked by pin bolt 114, and serves, in cooperation with cam 112, to define the axial position of the tube with respect to plate 110.

Bracket plate 110, which supports pivot 42 of lever 41 as well as journaling rod 106, is flanged as indicated at 118, 119, 120 for strength and to form a partial housing for the mechanism. It is mounted, preferably by welding, on the under face of the horizontal flange 10a of car sill 10 (Fig. 5). The right hand portion of plate 110, as seen in Figs. 1 and 2, is outwardly offset at 121 to form a housing around sheave 34. The drive shaft 26 is supported on plate 110 only indirectly through lever 41 and pivot 42.

Returning now to the transmission disabling mechanism proper, a rigid lift arm 125 extends radially from rod 106 just inward of spring 100, and its bent end 126 enters a long slot 127 in lift link 128. That link is pivoted at 130 on the swinging end of arm 64, gusset plate 76 providing a convenient support for the pivot. In normal operating position, as shown in Figs. 1-2 and 5, hand lever 109 is in the lower one of the two lockable positions, lying between the lower end of vertical flange 119 of plate 110 and the left hand edge of lower horizontal flange 119, where it is retained by the notch 140, cut in that edge (see Figs. 2 and 5). In that lever position, rod 106 is rotated counterclockwise, as seen, for example, in Fig. 1, into such a position that cam 112 is lifted free of the end 43 of lever 41, and lift arm 125 is free in slot 127 of link 128. The disabling linkage is thus effectively disconnected from the transmission mechanism. Spring 100 thus is free to act in the manner already described to render effective the three transmission devices 30, 60 and 80.

Lever 109 is releasable from its lower, or transmission actuating, position by first lifting it out of notch 140 in flange 118, then springing it back until it can be swung upward behind flange 119. It can then be lifted, sliding along the inner vertical edge of flange 119, until it is above the lip 142 which forms locking notch 144 in the upper edge of that flange (Fig. 5). The resilience of the lever tends to spring it outwardly so that it drops naturally into notch 144 and is thus locked by lip 142 in its upper, or transmission disabling, position. In that position of lever 109, rod 106 is rotated clockwise into the position shown in Fig. 4, in which the flat end 113 of cam 112 is pressed flatly against the upper surface of lever end 43, swinging lever 41 counterclockwise and lifting the outer end of drive shaft 26 to disable transmission 30. At the same time lift arm 125 at the inboard end of rod 106 is swung upward to engage the upper end of slot 127 in link 128 and lift roller 60 clear of drum 55, disabling the

drive from the drum. In the illustrated embodiment of the invention, transmission 80 is not disabled by actuation of lever 109, since a counterclockwise torque (as seen in Fig. 4) continues to be exerted on arm 64 by the downward spring force at 78 and the lifting force of link 128 applied at pivot 130. That torque tends to straighten the toggle linkage 64, 68, holding belt 86 tight. The lifting action which moves roller 60 away from drum 55 is thus a swinging of the entire toggle linkage about the link axis, which is the axis of shaft 26.

The transmission disabling action of handle 109, just described, completely disconnects the principal transmission elements (including roller shaft 62 and drive shaft 26) from the car running gear on the one hand and from accessory shaft 22 on the other. Thus unnecessary wear of the transmission mechanism is avoided both when the car is operated without use of the accessory and when the accessory is driven from some power source other than the car motion. Belt guard 150, mounted as by bracket 151 on shaft housing 28, provides a support for belt 32 when the belt tension is relieved. The belt is thus lifted from sheave 24 on the accessory shaft whenever the transmission is disabled, as shown in Fig. 4. Hence the belt is not worn by its own weight dragging on sheave 24 when the accessory shaft is driven by means other than the car running gear, as, for example, by an electric motor, not shown.

It will be evident from the above description of an illustrative preferred embodiment of the invention that the mechanism is subject to many variations of design without departing from the scope and spirit of the invention. For example, the arrangement of the parts on the car, with relation to the wheel and axle unit, to the car body, and to each other, is subject to wide variation as will be evident. And the toggle linkage can be varied in a number of ways, which may retain the overall functioning of the preferred form, or may introduce new functions.

For instance, Fig. 6 illustrates in schematic form an illustrative embodiment in which the two members of the toggle linkage, arm 64a and link 68a, form an acute, rather than an obtuse, angle. A typical point of application of a resilient transmission actuating force (such as that of spring arm 104 in the modification of Figs. 1-5) is indicated by the arrow 78a. A force so applied tends firstly to swing the toggle linkage 64a, 68a as a unit about the axis of shaft housing 28 in a direction (counterclockwise as seen in Fig. 6) to press roller 60 into driven engagement with drum 55; and secondly to swing arm 64a relative to toggle link 68a about toggle axis 66a in a direction to increase the toggle angle and thereby render transmission 80 effective. A transmission disabling force can be applied (as in the preferred form) substantially at shaft 62, as indicated in Fig. 6 by the arrow 128a. Such a force lifts roller 60 clear of drum 55, while maintaining transmission 80 in effective condition (as in the preferred modification). If, instead, a lifting force is applied to arm 64a at such a point as is indicated by the arrow 128c between point 78a and toggle axis 66a, the couple exerted on arm 64a by that lifting force, in cooperation with the spring-applied force at 78a, is counterclockwise and tends to decrease the toggle angle at 66a, disabling transmission 80. If a suitable stop is provided to limit the decrease of the toggle angle, which may, for example, result from contact of arm 64a with shaft housing 28, fur-

ther lifting at 128c will swing the toggle linkage 64a, 68a as a unit about shaft housing 28 to lift roller 60 clear of drum 55. The overall action of a transmission disabling force applied at 128c is therefore, in contrast to that of the preferred modification, to disable transmission 80 as well as the initial transmission from the wheel and axle unit. The same result can be accomplished with the toggle structure of the preferred modification by pivoting lifting link 128 at a point on arm 64 which is spaced outwardly on the arm from the line of action of the spring force applied at 68. In general it is preferred to maintain belt 86 tight enough at all times to avoid any possibility of its dropping off its pulleys.

Fig. 7 is a diagrammatic representation of a further illustrative modification in which the roller carrying arm 64b and the toggle link 68b form an obtuse angle, as in the preferred form, but in which the resilient actuating force is applied inwardly of roller shaft 62. The point of application of that force, indicated in Fig. 7 by the arrow 78b, is on the toggle link rather than on the arm 64b, but the effect of that force is, as before, to straighten the toggle linkage, making transmission 80 effective, and also to swing the toggle linkage as a unit about the link axis, pressing roller 60 into driven contact with drum 55.

Fig. 7 illustrates also the fact that the toggle link can be entirely independent of shaft housing 28. Specifically, it shows toggle link 68b pivoted at 28b directly on bracket 38 at a point eccentric of shaft housing 28. The pivot 28b is preferably, although not necessarily, close to the axial plane of transmission 80, as shown, since swinging of the toggle linkage as a unit about the pivot then has a minimum effect on the tightness of the belt. An advantage resulting from a toggle pivot independent of shaft housing 28 is that the mounting of the housing on the car body then need not permit rotation of the housing about its longitudinal axis. The same result can be obtained, for example, by pivoting toggle link 68 directly on shaft 26 beyond the inner end of housing 28, or between the two journal bearings of shaft 26, those bearings then being independently mounted on the car body and housing 28 being omitted. Alternatively, the toggle link can be pivoted on housing 28, rather than rigidly connected to it as in the preferred modification.

Although the type of spring shown at 100 in Fig. 2 is preferred, it can be replaced for example, by a leaf spring mounted centrally on rod 106 or directly on the car body, with its ends resting respectively on arm 64 and shaft housing 28. Alternatively, separate springs may be employed for rendering effective one or more of the three transmission stages of the drive mechanism. In those transmissions rollers or the like, as illustrated at 60, can be used as transmission elements interchangeably with belt-type drives, as illustrated at 30 and 80, the relative motions of two connected shafts for transmission actuation being of course opposite for the two types of transmission.

And modifications may also be made with relation to the structure of the shaft carrier (housing 28). The primary function of that carrier is to form, or to carry, the journaling for shaft 26. In the described preferred design the carrier completely encloses and protects the shaft between its two ends and the shaft is journalled in bearings located in the ends of the carrier tube. However, that particular design is not necessary to

the performance of the primary functions. As is obvious, the carrier need not surround the shaft. And neither need it be continuous between the ends of the shaft. For instance, the illustrated carrier may be visualized as cut into two or more pieces at a transverse plane located between yoke 40 and spring bearing 90, and/or located between 90 and the inner end. If the two or three divisional parts of the carrier are each journalled on the shaft, then the following functional observations may be made. The outer part, at yoke 40, is nothing more than a journal in which the shaft is supported on lever 41. The central part is nothing more than a journal through which spring pressure is applied to the rotary shaft to swing it down. And the inner part then functions merely as a journal mounting for the inner end of the shaft, allowing the requisite swinging movement of the shaft as well as its rotation. In the preferred arrangement that inner part also functions to form the axis about which toggles 69 swing; but, as shown in Fig. 7, it is not necessary for that function to be performed by the shaft journal, as the toggle pivot can be offset from the shaft axis. The illustrated carrier can thus be looked at as means for journaling and mounting the inner end of the shaft for its requisite movements, for effectively applying the spring pressure to the shaft at any desired point in the shaft length; and for journaling the outer end of the shaft in a mounting (lever 41) which allows that end of the shaft to move in a direction to and from the driven shaft 22.

35 The modifications which have been particularly spoken of are not intended to be exhaustive; as many others will occur to those skilled in the art.

- I claim:
1. Driving mechanism for driving a shaft from a rotatable drum the axis of which is spaced from the shaft axis, said driving mechanism including a toggle link pivoted for swinging movement about a link axis approximately coinciding with the shaft axis, an arm mounted on the toggle link for swinging movement about a toggle axis thereon generally parallel to the link axis, an intermediate shaft journaled on the swinging arm, a transmission element mounted on the intermediate shaft and forming a part of a transmission between the drum and the intermediate shaft which is rendered effective by swinging movement of the arm and toggle link as a unit about the link axis in a predetermined actuating direction, and a transmission between the intermediate shaft and the driven shaft which is rendered effective by swinging movement of the arm about the toggle axis in a predetermined actuating direction relative to the toggle link.
  2. Driving mechanism as defined in claim 1 and including unitary resilient means tending to swing the arm and toggle link as a unit about the link axis in the said first mentioned actuating direction and also tending to swing the arm about the toggle axis in the said second mentioned actuating direction relative to the toggle link.
  3. Driving mechanism as defined in claim 1 and including means engageable with the arm to swing the arm and toggle link about the link axis in a direction opposite to the said first mentioned actuating direction.
  4. Driving mechanism for driving a shaft from a rotatable drum the axis of which is spaced from the shaft axis, said driving mechanism including

11

a toggle link pivoted for swinging movement about a link axis approximately coinciding with the shaft axis, an arm mounted on the toggle link for swinging movement about a toggle axis thereon generally parallel to the link axis, an intermediate shaft journaled on the swinging arm, a roller mounted on the intermediate shaft and adapted to engage the periphery of the drum by virtue of swinging movement of the arm and toggle link as a unit about the link axis in a predetermined roller actuating direction, a transmission between the intermediate shaft and the driven shaft which is rendered effective by swinging movement of the arm about the toggle axis in a predetermined shaft actuating direction, and resilient means exerting on the arm a resilient force directed along a line spaced from the axis of the intermediate shaft, and tending to swing the arm and toggle link about the link axis in the said roller actuating direction, and thereby to urge the roller against the drum, said resilient means, in cooperation with the reaction force exerted by the drum on the roller, exerting upon the arm a torque tending to swing the arm about the toggle axis in the said shaft actuating direction.

5. Driving mechanism as defined in claim 4 and including means manually operable to engage the arm and to exert thereon a force directed generally along the line of the said reaction force, thereby swinging the arm and toggle link about the link axis in a direction opposite to the said roller actuating direction, and maintaining the said torque.

6. Driving mechanism for an accessory carried by the body of a car structure which has a running gear element affording a driving drum, the accessory having an operating shaft; said driving mechanism including a driving shaft, journal means supported on the car body for one end of the driving shaft and capable of swinging motion about an axis transverse of the shaft, journal means for the other end of the driving shaft capable of translational motion toward and from the accessory operating shaft, a transmission element mounted on the said other end of the driving shaft and forming part of a transmission between the two said shafts which is rendered effective by translational motion of the shaft end in a predetermined actuating direction, an arm mounted for independent swinging movement about two generally parallel axes, an intermediate shaft journaled on the swinging arm, a transmission element mounted on the intermediate shaft and forming part of a second transmission between the drum and the intermediate shaft which is rendered effective by swinging movement of the arm about one of its said axes in a predetermined actuating direction, a third transmission by which the driving shaft is drivable from the intermediate shaft and which is rendered effective by swinging movement of the arm about the other of its said axes in a predetermined actuating direction, the effectiveness of the third transmission being relatively independent of swinging movement of the arm about its said one axis, and resilient means tending to swing the arm about its said one axis in the said second transmission actuating direction, and tending to swing the arm about its said other axis in the said third transmission actuating direction.

7. Driving mechanism as defined in claim 6 and in which the said resilient means comprises a unitary spring element, and tends also to swing the driving shaft in the said first transmission actuating direction.

12

8. Driving mechanism as defined in claim 6 and including means engageable with the driving shaft for causing it to swing in the direction opposite to the said actuating direction, and engageable with the arm for causing it to swing about its said one axis in a direction opposite to the said actuating direction.

9. Driving mechanism for an accessory carried by the body of a car structure which has a running gear element affording a driving drum, the accessory having an operating shaft; said driving mechanism comprising a shaft carrier mounted on the car body for rotational motion about its longitudinal axis and for swinging motion about a transverse axis, a driving shaft longitudinally journaled in the shaft carrier, a transmission element mounted on the shaft at a point spaced from the said transverse axis and forming part of a transmission between the driving shaft and the accessory shaft, said transmission being rendered effective by swinging motion of the carrier about the transverse axis in a predetermined transmission actuating direction, a transverse toggle arm mounted on the shaft carrier, a roller arm pivoted at one end on the toggle arm on a toggle axis generally parallel to the longitudinal axis of the carrier, a roller shaft journaled on the roller arm and carrying a roller adapted to engage the running gear drum by virtue of swinging movement of the roller shaft about the longitudinal carrier axis toward the drum, transmission elements mounted respectively on the roller shaft and the driving shaft and forming part of a transmission between those two shafts which is rendered effective by swinging of the roller arm relative to the toggle arm about the toggle axis in a predetermined shaft actuating direction, spring means arranged to exert a resilient force upon the roller arm tending to swing the roller shaft toward the drum to engage the roller with the drum, the line of said force being so spaced from the axis of the roller shaft that the said force and the reaction force of the drum against the roller produce a couple tending to swing the roller arm about the toggle axis in the said shaft actuating direction, and spring means arranged to exert a resilient force upon the shaft housing tending to swing it about its said transverse axis in the said transmission actuating direction.

10. Driving mechanism as defined in claim 9 and including, control means for the roller arm capable of two alternative conditions, in one of which the control means are effectively disconnected from the arm and in the other of which the control means exert on the arm a force acting in opposition to the first mentioned resilient force to move the roller out of drum engagement, and control means for the shaft housing capable of two alternative conditions, in one of which the control means are effectively disconnected from the housing and in the other of which the control means exert on the housing a force acting to swing the housing about its said transverse axis in opposition to the second mentioned resilient force, thereby rendering ineffective the first mentioned transmission.

11. Driving mechanism as defined in claim 10, and in which the roller disengaging force of the roller arm control means is applied to the roller arm at such a point that the latter force and the first mentioned resilient force produce a couple tending to swing the roller arm about the toggle axis in the same direction as the first said couple.

12. Driving mechanism as defined in claim 10, and including an element manually shiftable between two alternative positions, and connections between said element and the two said control means adapted to shift the control means between their respective first mentioned and second mentioned conditions in response to movement of the element between its two positions.

13. Driving mechanism as defined in claim 9, and in which the two said spring means comprise a unitary elongated spring element, means adapted to apply force from one end of the spring element at a predetermined point of the roller arm and means adapted to apply force from the other end of the spring element at a predetermined point of the shaft carrier.

14. Driving mechanism for an accessory carried by the body of a railway car structure and having an operating shaft, said car structure including a drum rigidly mounted on a car axle between the car wheels, said driving mechanism comprising a driving shaft extending transversely of the car and journaled on the car body, the journal means permitting translational movement of the outboard end of the driving shaft toward and from the accessory shaft, power transmission means between the outboard end of the driving shaft and the accessory shaft, said transmission means being rendered effective by the said translational movement of the driving shaft in a predetermined accessory actuating direction, a roller arm pivoted on an axis transverse of the car, a roller shaft journaled on the arm and carrying a roller adapted to engage the drum by virtue of swinging movement of the roller arm about its pivot axis in a predetermined roller actuating direction, power transmission means between the roller shaft and the driving shaft, a rod mounted on the car body transversely of the car and axially rotatable between two alternative positions, a helical spring surrounding the rod and guided thereby, one end of the spring extending generally radially from the axis of the helix and exerting upon the roller arm a resilient force tending to swing the arm in the said roller actuating direction, and the other end of the spring extending generally radially from the axis of the helix and

exerting upon the driving shaft a resilient force tending to move its outboard end in the said accessory actuating direction, mechanical means operatively associated with the rod and acting by virtue of rotation of the rod into one of its said positions to swing the roller arm about its pivot axis against the force of the spring and to move the outboard end of the driving shaft in translation against the force of the spring, thereby moving the roller out of drum engagement and disabling the transmission means between the driving shaft and the accessory shaft.

15. Driving mechanism for driving a shaft from a rotatable drum the axis of which is spaced from the shaft axis, said driving mechanism including an arm mounted for independent swinging movement about two generally parallel axes, an intermediate shaft journaled on the swinging arm, a transmission element mounted on the intermediate shaft and forming part of a transmission between the drum and the intermediate shaft which is rendered effective by swinging movement of the arm about one of its said axes in a predetermined actuating direction, a second transmission by which the driving shaft is drivable from the intermediate shaft and which is rendered effective by swinging movement of the arm about the other of its said axes in a predetermined actuating direction, the effectiveness of the second transmission being relatively independent of swinging movement of the arm about its said one axis, and resilient means tending to swing the arm about its said one axis in the said actuating direction of the first mentioned transmission, and tending to swing the arm about its said other axis, in the said actuating direction of the second mentioned transmission.
